United States Patent

Des. 235,844
Patented July 15, 1975

235,844

PUNCH TOOL

Loren A. Matthews, Haslett, Mich., assignor to Matt
Tool Corporation, Haslett, Mich.

Filed Nov. 8, 1973, Ser. No. 413,762

Term of patent 14 years

Int. Cl. D8—05

U.S. Cl. D8—52

FIG. 3

FIG. 4

FIG. 2

FIG. 5

FIG. 1

FIG. 7

FIG. 6

FIG. 1 is a front elevation view of the punch tool showing my new design.

FIG. 2 is a right side elevation view thereof, the opposite side being a mirror image thereof.

FIG. 3 is a rear elevation view thereof.

FIG. 4 is a top view thereof.

FIG. 5 is a bottom view thereof.

FIG. 6 is a side elevation view thereof showing the punch tool in its open position for purposes of illustration.

FIG. 7 is a cross-sectional view thereof taken on line 7-7 of FIG. 6.

FIG. 8 is a cross-sectional view thereof taken on line 8-8 of FIG. 2.

I claim:

The ornamental design for a punch tool, as shown and described.
